Primary Examiner — Barbara Fox*Assistant Examiner* — Messina L Smith(74) *Attorney, Agent, or Firm* — Parker Poe Adams and Bernstein LLP(57) **CLAIM**

The ornamental design for a double snap hair clip, as shown and described.

DESCRIPTION

FIG. 1 is a perspective view of a double snap hair clip showing the new design;

FIG. 2 is a top plan view thereof;

FIG. 3 is a bottom plan view thereof;

FIG. 4 is a first side elevation view thereof;

FIG. 5 is an opposing second side elevation view thereof;

FIG. 6 is a front elevation view thereof; and,

FIG. 7 is a rear elevation view thereof.

The broken lines in the drawings depict portions of the double snap hair clip that form no part of the claimed design.

1 Claim, 6 Drawing Sheets(56)
